A. ALARY.

HINGE,

APPLICATION FILED FEB. 24, 1919.

1,379,951

Patented May 31, 1921.

Alphonse Alary

W. Clinton

Attorney

UNITED STATES PATENT OFFICE.

ALPHONSE ALARY, OF ST. CASIMIR, QUEBEC, CANADA.

HINGE.

1,379,951.

Specification of Letters Patent. Patented May 31, 1921.

Application filed February 24, 1919. Serial No. 278,716.

To all whom it may concern:

Be it known that I, ALPHONSE ALARY, a subject of the King of Great Britain, residing at St. Casimir, Portneuf county, Province of Quebec, Canada, have invented certain new and useful Improvements in Hinges; and I do hereby declare that the following is a full, clear, and exact description of the invention, such as will enable 10 others skilled in the art to which it appertains to make and use the same.

The present invention relates to hinges for doors and the like, and an object of the present invention is to provide a hinge of a 15 simple and strong construction that may be readily applied to any door and which will hold the door in opened or closed position.

With the above and other objects in view which will hereinafter appear as the description continues, the invention consists 20 of the novel features of construction, combination and formation of parts as will be hereinafter more fully described and particularly pointed out in the appended claim.

25 In the accompanying drawings has been shown a simple and preferred form of the invention, it being, however, understood that no limitation is necessarily made to the precise structural details herein exhibited, 30 but the right is hereby reserved to any changes, alterations or modifications to which recourse may be had that come within the scope of the claims without departing from the spirit of the invention or sacrificing 35 the efficiency of the same.

In the accompanying drawings:

Figure 1 is a front elevation of a door having the hinge applied thereto;

Fig. 2 is a detail section through the upper end of the door and the door casing;

Fig. 3 is an enlarged detail view of one portion of the hinge;

Fig. 4 is a similar view of the lower portion of the hinge;

Fig. 5 is a plan view of the hinge when applied; and

Figs. 6 and 7 are elevations of double-way hinges.

Referring now more particularly to the 50 accompanying drawings wherein like and corresponding parts are designated by similar reference characters throughout the several views.

The double-way hinges, as better illustrated in Figs. 6 and 7, comprise two sec-

tions, each of which consists of a plate 1 which is to be secured to the door casing and door respectively. The section secured to the door casing is provided with a sleeve 2 in which is adapted to be seated a stub 60 axle or lug projection 3 carried by the section secured to the door. These hinges support the door and permit the same to be readily opened or closed.

The purpose of the present invention is 65 to improve this class of hinges so that the door may be retained in its opened or closed positions. The door as herein shown indicated by the numeral 4 is seated within the doorway and supported within the door casing 5. The upper hinge 6 as shown in Fig. 1 may be of the construction as shown in Figs. 6 and 7, but the lower hinge 7 is made in accordance with the present invention. This hinge comprises two sections one of 70 which consists of a plate 8 adapted to be secured to the door and formed with this plate is a sleeve 9 having its upper end closed. The other section of this hinge comprises a plate 10 which is secured to the door 75 casing by means of the set screws or any other suitable fastening members and is provided with a projecting portion 11. Journaled within this projection 11 is a roller 12 and formed contiguous with this projection is a stub shaft or lug 13 which is to be received by the sleeve 9. The lower face of this sleeve 9 is beveled so as to provide an incline 14 and formed within this lower edge is a recess 15. When the door is mounted 80 within the door casing the sleeve 9 extends over the stub shaft 13 and the roller 12 rides upon the lower edge of this sleeve. When the door is being opened this roller 12 rides upon the incline 14 and if the door be 85 released it will readily close due to this construction, as the roller 12 normally assumes the position as shown in dotted lines in Fig. 3 and when in this position the door is closed. When the door is swung open until 90 it makes a quarter turn the roller 12 will be seated within the recess 15 whereby the door will be retained in this opened position. As the door is swung open it will have a 95 tendency to rise and the lower edge of the sleeve 9 rides upon the roller 12 and to facilitate the opening of the door the upper edge thereof is cut away as indicated by the numeral 16, so that as the door is being opened it may rise and pass by the door 100 105 110

casing due to this cut away portion. Therefore, when the door is closed it will be tightly seated within the door casing.

Having thus fully described my invention, what I claim as new and desire to secure by Letters Patent is:

A hinge of the character described comprising an upper and lower plate each of a substantially rectangular formation, a projection formed upon the outer edge of the lower plate at the upper end thereof, a stub shaft formed integral on the outer edge of said projection, a slot extending transversely therein, a roller journaled in said slot having its outer periphery extending above the edge of said projection, a sleeve formed at

the lower end of the upper plate on the outer edge thereof and adapted to receive said stub shaft, said sleeve having its upper end closed and its lower edge adapted to 20 rotate over said roller, said lower edge being inclined upwardly toward the plate whereby the door will normally swing closed by its own weight and recesses formed on said lower edge of the sleeve diametrically opposite thereon for engagement with said roller and adapted to secure the door in an open or closed position. 25

In witness whereof I have hereunto set my hand.

ALPHONSE ALARY.
